UNITED STATES PATENT OFFICE

2,334,209

MULTIPLE POWER OPERATED MECHANISM

Ralph E. Lamberton, Michigan City, Ind., assignor to Sullivan Machinery Company, a corporation of Massachusetts

Application October 21, 1941, Serial No. 415,958

5 Claims. (Cl. 254—187)

My invention relates to apparatus for controlling the driving of a plurality of power operated mechanisms from a prime mover, and more particularly to improved means for controlling selectively the driving of combined pumping and hoisting mechanisms from a common source of power.

It is often necessary to have available for certain types of construction work a source of compressed air for pneumatic tools and a hoist for moving materials. The expense involved in providing a compressor and a hoist driven by separate prime movers is sometimes prohibitive. The expense may be reduced somewhat by providing an air operated hoist, but the size of the hoist may be limited where it is to be operated by air supplied by the compressor. By providing a single prime mover and means for enabling the power of the same to be utilized selectively at any time to cause a compressor to deliver air or a hoist to be operated, and so that the hoist may be driven while the stored air pumped by the compressor is being used, a very desirable piece of equipment is made available. If, as in my invention, control means are provided whereby the load of the compressor and the speed of the prime mover may be controlled automatically when the compressor is driven to perform its pumping functions, and the compressor-imposed load is reduced and the speed of the prime mover is made responsive continuously to a manual control when the hoist is connected in driving relation with the prime mover, a very satisfactory compressor and hoist unit may be provided.

An object of my invention is to provide an improved apparatus in which a pumping device and a separate power driven mechanism may be selectively driven by a single power unit. Another object is to provide improved means for controlling selectively the delivery of fluid by a pumping apparatus and the operation of a hoist from a single power unit. Still another object is to provide a compressor and a hoist adapted selectively to be operated to perform their respective functions by a single power unit and having improved means for controlling the supply of operating fluid to the power unit and the unloading of the compressor during the driving of the hoist. Other objects and advantages will appear in the course of the following description.

In the accompanying drawings in which for purposes of illustration one form of my invention has been shown:

Fig. 1 is a side elevational view with parts 55

broken away, showing my invention in its preferred form.

Fig. 2 is a plan view, with parts broken away, of the mechanism shown in Fig. 1.

Fig. 3 is an enlarged sectional view through an unloading device, a cylinder head and a portion of a cylinder, taken on the plane including the axis of the cylinder.

Fig. 4 is an enlarged vertical sectional view through a control valve, the section being taken on line 4—4 of Fig. 2.

Fig. 5 is a view similar to Fig. 4, showing the valve in a different position.

Fig. 6 is an enlarged vertical sectional view through another control valve, taken on line 6—6 of Fig. 2.

Fig. 7 is a view similar to Fig. 6, showing the valve in a different position.

There is shown in this illustrative embodiment 20 of the invention a power unit 1, a pumping apparatus 2 in the form of a compressor, and a power driven device 3, shown herein in the form of a hoist, mounted on a base structure generally designated 4. Mounted on the base structure and 25 surrounding the power unit and the compressor is a casing 5. This apparatus and certain of the control devices to be described herein are similar to that shown and described in my copending application, Serial No. 379,943, filed February 21, 30 1941.

The power unit may assume various forms, but is shown herein as an engine of the internal combustion type arranged with its power shaft extending longitudinally of the base structure. A 35 radiator 6 is mounted on the end of the base structure adjacent the engine 1 and contains cooling fluid for the latter. At the side of the engine is a throttle device 7 which is controlled by manually operated and automatically operated 40 means, generally designated 8, which will shortly be described more in detail.

The compressor 2 shown herein is of the multi-cylinder, single stage type having cylinders 10 and 11 extending radially from a crank case 13, 45 and the compressor crankshaft, a portion of which is shown at 14, is arranged in alinement with the power shaft of the engine and is driven directly thereby. A fan 15 is connected to a frame 16 attached to the compressor crankcase 50 and is driven by a belt 17 engaging a pulley 18 on the compressor crankshaft for circulating cooling air through the casing 5 over the compressor and engine.

The compressor cylinders are identical in construction, and each comprises, as shown in Fig.

3, a cylinder member 20 having a bore 21 within which a piston 22 may be reciprocated by the compressor crankshaft through a connection not shown. A valve mechanism, generally designated 23, and a cylinder head 24 are arranged in an enlarged bore 25 formed in the cylinder member, and the cylinder head is secured as by bolts 26 to the cylinder member in engagement with the valve mechanism for clamping the latter against a shoulder 27 at the junction of the bores 21 and 25. A conduit 28 connected to the side of the cylinder member, as by bolts 29, has an air cleaner 30 mounted upon its outer end and opens at its inner end into a passage 31 communicating with the cylinder bore 21 past an inlet valve 32. A discharge valve 33 controls the flow of compressed air between the cylinder and a passage 34 opening into a discharge conduit 35. The discharge conduits of the cylinders 10 and 11 are connected to a common conduit 36 which delivers the compressed air to a storage tank 37 supported above the base structure by support members 38 and 39.

Mounted on the outer ends of each of the compressor cylinders are unloading devices generally designated 40. Each of these unloading devices includes a member 41 and plates 42 and 43 attached to the cylinder head as by bolts 44. Formed between the plate 43 and the member 41 is a chamber 45 within which a reduced portion 46 of a plunger 47 projects through openings 48 and 49 formed in the member 41 and the plate 42 respectively. An enlarged portion 50 of the plunger is received in a recess 51 formed in the cylinder head and carries rods or fingers 52 extending through openings 53 in the cylinder head into the intake passage 31 and engageable at their lower ends with the inlet valve to move the latter from its seat and unload the compressor when the plunger is forced downwardly. The plunger 47 is normally held in its raised position by a spring 55 arranged in the recess 51 beneath the plunger 47 and shown herein as being of the bowed plate type. The spring 55 and the plunger are guided by a pin 56 fixed to the cylinder head and projecting upwardly through an opening in the spring into a recess 58 formed in the plunger. Surrounding the reduced portion 46 of the plunger just above the plate 42 is a packing 60 sealingly engaging the plunger for preventing the escape of pressure fluid from the chamber 45 into the recess 51. Mounted on the plate 43 are members 61 and 62 held in place by bolts 64 extending through openings formed in the plate 43 and in a flange on the member 41 as shown in Fig. 3. Formed between the members 61 and 62 is a chamber 65, and a flexible diaphragm 66 is received in this chamber and clamped between the members 61 and 62. A plunger 67 is arranged in the chamber 65 and has an enlarged head 68 which is held in engagement with the diaphragm 66 by a coil spring 69 which rests on the member 62. A reduced portion 71 of the plunger 67 extends downwardly through openings in the member 62 and the plate 43 into the chamber 45 in axial alignment with the plunger 47. A packing 74 fits within a recess in the member 62 surrounding the reduced portion 71 and sealingly engages the latter for preventing escape of pressure fluid from the chamber 45 to the chamber 65. It will be observed that the plunger 47 may be moved to its lower position to effect opening of the inlet valve and unloading of the compressor cylinder by admitting pressure fluid to the chamber 45 where it acts

directly on top of the plunger, or by admitting pressure fluid to the space above the diaphragm 66 in the chamber 65 to force the diaphragm downwardly and move the plunger 67 against the plunger 47, forcing the latter downwardly to its unloading position. A vent 75 leads from space 65 below the diaphragm 66.

To effect automatic unloading of the compressor and reloading thereof in accordance with compressor discharge pressure variations there are provided conduits 76 opening into the chambers 45, and these conduits are connected to a common conduit 77 which is normally connected through a device 78, which permits free flow of pressure fluid toward the unloading devices and delays venting of fluid from the devices, to a pilot valve 79, which may be of any suitable type and which is herein illustrated as a so-called R. C. pilot valve, connected in the compressor discharge conduit 36. This pilot valve is operative upon the attainment of a predetermined desired maximum compressor discharge pressure to supply fluid from the discharge line past the device 78 to the conduit 77, and upon a drop in pressure to a predetermined minimum value, to vent the conduit 77.

In order to unload the compressor when the same is operating loaded and it is desired to connect the hoist for drive by the engine, conduits 80 are provided opening into the chambers 65 above the diaphragms 66, and these conduits are connected to a common conduit 81 opening into a bore 82 in a valve casing 83, as shown in Figs. 4 and 5. Arranged in the crank case of the compressor is a lubricant pump, not shown, for supplying lubricant to parts of the compressor mechanism, and connected to this lubricant pump is a conduit 84 which opens into the bore of the valve casing 83. A conduit 85 also communicates with the bore of the valve casing and leads to the crankcase of the compressor for returning fluid thereto. A valve 87 is rotatably mounted in the bore 82 of the valve casing and is provided with a groove 88 for connecting the conduits 81 and 84 when it is in one of its limiting positions, and for connecting the conduits 81 and 85 when it is in another limiting position. An arm 90 is connected to the valve 87, and a rod 91 connects the end of the arm to a manually operated lever 92, as shown in Fig. 1. When the lever 92 is moved in a counter-clockwise direction, as viewed in Fig. 1, the valve 87 is moved to the position shown in Fig. 5 for connecting the conduits 81 and 84 through the groove 88 and supplying oil under pressure from the lubricant pump to the upper side of a diaphragms 66, thereby forcing the diaphragms downwardly and moving the plungers 47 to their unloading positions.

In order to drive the hoist, there is provided a coupling 95 connecting a shaft 96 to the end of the compressor crankshaft 14, and the shaft 96 is connectable through a clutch mechanism, generally designated 97, to a shaft 98. The clutch mechanism is similar to that described in detail in my above mentioned copending application and, since it forms no part of the present invention, it will not be described in detail here. The operating lever 92 controls the operation of the clutch mechanism and effects a connection and a disconnection of the clutch when it is moved in counter-clockwise and clockwise directions, respectively. Power is transmitted from the shaft 98, as shown in Fig. 2, through a flexible drive member 99, such as a belt or chain, to a shaft 100 which is connected through suitable gearing,

not shown, to the drum 101 of the hoist 3. Suitable means are provided for controlling the operation of the drum and are shown here as including operating levers 102, 103 and 104. The lever 102 is connected through a link 105 to a shaft 106 which effects operation of a clutch, not shown, controlling the drive of the drum. The lever 103 is connected through a link 107 to a shaft 108 on which a dog 109 is fixed and is movable by the shaft 108 into engagement with teeth 110 on the drum for locking the latter against rotation in an unwinding direction. The lever 104 is connected through a link 111 to a shaft 112 and controls the operation of a brake, not shown, for braking the rotation of the drum. It will be noted that, since a control of the hoist is effected by the levers last described, after control lever 92 has been operated to connect the shafts 96 and 98, the other control mechanism will have had time to become operative before the hoist load is applied to the engine.

Referring to the control means 8 for the throttle device 7 of the engine, it will be noted that a rod 115 is connected at one of its ends to the throttle and is connected at its other end to an arm 116 mounted for pivotal movement at 117. Suitable pressure responsive means 118 are provided for effecting a swinging of the arm 116 about its pivot to move the rod 115 in a direction to close the throttle valve when pressure fluid is supplied thereto. This control means is a standard piece of equipment that may be purchased in the open market and, since the present invention is not in any way dependent on the specific form of this device, further description of the same is unnecessary. A conduit 120 leads from the device 78 at a point communicating freely with the pilot valve 79 (i. e. it is not subject to restricted flow in a return direction by the device 78), and is connected through a valve, generally designated 121, to a conduit 122 leading to the pressure responsive means 118. A lever 123, pivotally mounted between its ends, operatively engages, at one of its ends, the rod 115 and is connected at its other end to a rod 124 which is connected to a lever 125 that may be manually operated to open or close the throttle. The control valve 121, as shown in Figs. 6 and 7, includes a valve casing 126 having ports 127 and 128 opening into a valve bore 129. The conduits 120 and 122 communicate through the ports 127, 128 respectively with the valve bore, and a valve element 130, rotatably mounted within the valve bore, is provided with a groove 131 for connecting the ports 127 and 128 when the valve is in one of its limiting positions. A groove 132 is formed in the valve for connecting the port 128 with a vent port 133 when the valve is in another of its limiting positions. Connected to the valve, as shown in Fig. 1, is an arm 135 having its outer end connected to a rod 136 which is connected to an arm 137 fixed to one end of the valve 87.

The mode of operation of the mechanism described above is as follows: Assuming that the pressure in the receiver is low and that it is desired to drive the compressor for pumping air to the receiver, the lever 92 will be moved in a clockwise direction to disconnect the hoist, to move the valve element 130 of the valve 121 to its position connecting conduits 120 and 122, and to move the valve 87 to a position for venting fluid from the spaces above the diaphragms 66 to the compressor crankcase. Now if the engine 1 is running, the compressor is driven loaded and pumps air to the receiver until a predetermined maximum dis-

charge pressure is reached. During this time, the supply of operating fluid to the engine may be controlled by adjusting the throttle 7 through the operating lever 125, the rod 124, the lever 123 and the rod 115. When the maximum desired pressure is reached, the pilot valve 79 operates to supply pressure fluid from the discharge line through the device 78, conduit 77 and the conduits 76 to the chambers 45 where it acts on the plungers 47 moving the latter to their lower unloading positions. At the same time, pressure fluid is supplied past the pilot valve and past, but not under the control of, the device 78, to the conduit 120, and past the valve 121 to the conduit 122 leading to the pressure responsive device 118 which is actuated to move the engine throttle towards its closed position. As long as the pressure in the discharge line remains high enough to hold the pilot valve open, pressure fluid is supplied to the unloading devices for the compressor and to the device 118, thereby causing the engine to drive the compressor unloaded at a slow speed. If it is desired at any time to connect the hoist in driving relation with the engine, the operating lever 92 is moved in a counter-clockwise direction for loading the clutch mechanism 97, for moving the valve 87 to a position connecting conduits 81 and 84, and for moving the valve element 130 of the valve device 121 to its position connecting conduit 122 to the vent port 133 through the groove 132. Oil is then pumped from the compressor crankcase through the conduit 84, past the valve 87, and through the conduit 81 and conduits 80 to the spaces above the diaphragms 66 for forcing the latter downwardly and moving the plungers 67 and 47 to positions effecting unloading of the compressor. Any pressure fluid in the throttle control device 118 is vented through the conduit 122 to the vent port 133 permitting the throttle to move toward its open position for speeding up the engine to carry its load. The speed of the engine will then, except as speed responsive or other devices may be provided, be regulated by the operator through the lever 125 and connected parts.

As a result of this invention there is provided an improved combination of a pumping apparatus and a separate power driven mechanism having improved means for selectively connecting the same in driven relation with a power unit. It will be noted that there is provided improved means whereby a single power unit may be employed for driving a pumping apparatus at different speeds, varying automatically in accordance with discharge pressure, or for driving a separate power driven mechanism at different speeds, adjusted by manual control means, while the pumping apparatus is unloaded. It will further be noted that there is provided improved unloading means for a compressor, the unloading means being responsive to pressure fluid supplied from different sources. Other advantages of the invention will be clearly apparent to those skilled in the art.

The improved unloading means per se disclosed in this application is being claimed in my copending application Serial No. 448,615, which is a continuation-in-part of this present application.

While there is provided in this application one form which the invention may assume in practice, it will be understood that this form is shown for purposes of illustration and that the invention may be modified and embodied in various other forms without departing from its spirit or the scope of the appended claims.

What I claim as new and desire to secure by Letters Patent is:

1. In combination, a power unit, a pumping apparatus connected for drive by said power unit, a pressure responsive device for controlling the supply of operating fluid to said power unit, pressure responsive unloading means for said pumping apparatus, means for conducting pressure fluid to said pressure responsive device and to said unloading means, means operative at a predetermined pump discharge pressure for supplying pressure fluid to said fluid conducting means, valve means for controlling the flow of pressure fluid through said conducting means to said pressure responsive device, means for conducting fluid under pressure from a separate source to said unloading means, valve means for controlling the flow of pressure fluid through said last mentioned means, a separate power driven mechanism adapted to be driven by said power unit, manually operated means for controlling the connection of said power driven mechanism in driven relation with said power unit, and means connected for operation with said manually operated means and adapted to effect actuation of said valve means to positions for cutting off the flow of fluid to said pressure responsive device and for supplying fluid to said unloading means when said manually operated means is operated to connect said power driven device in driven relation with said power unit.

2. In combination, a power unit, a compressor connected for drive by said power unit, a pressure responsive device for controlling the supply of operating fluid to said power unit, pressure responsive unloading means for said compressor, means for conducting pressure fluid to said pressure responsive device and to said unloading means, means operative at a predetermined maximum compressor discharge pressure for supplying pressure fluid to said fluid conducting means, valve means for controlling the flow of pressure fluid through said conducting means relative to said pressure responsive device, means for conducting fluid under pressure from a separate source to said unloading means, valve means for controlling the flow of pressure fluid through said last mentioned means, a hoist adapted to be driven by said power unit, a clutch mechanism for controlling the connection of said hoist in driven relation with said power unit, and means connected for operation with said clutch mechanism and adapted to effect actuation of said valve means to positions for cutting off the supply of fluid to said pressure responsive device and for supplying fluid to said unloading means when said clutch mechanism is actuated to connect said hoist in driven relation with said power unit.

3. In combination, a power unit, a compressor connected for drive by said power unit, a pressure responsive device for controlling the supply of operating fluid to said power unit, pressure responsive unloading means for said compressor, means operative at a predetermined maximum compressor discharge pressure for supplying pressure fluid to said pressure responsive device, said pressure fluid supplying means including compressor discharge pressure responsive valve means and a valve for controlling the flow of operating fluid relative to said pressure responsive device, said valve constructed and arranged so as, in one

position thereof, completely to vent pressure fluid from said pressure responsive device, means including a valve for supplying fluid under pressure to said unloading means, a power driven device adapted to be driven by said power unit, a clutch mechanism for controlling the connection of said power driven device in driven relation with said power unit, and means connected for operation with said clutch mechanism and adapted to effect actuation of said valves to positions for venting fluid from said pressure responsive device and for supplying fluid under pressure to said unloading means when said clutch mechanism is actuated to connect said power driven device in driven relation with said power unit.

4. In combination, a power unit, a pumping apparatus connected for drive by said power unit, a pressure responsive device for controlling the supply of operating fluid to said power unit, pressure responsive unloading means for said pumping apparatus, means for conducting pressure fluid relative to said pressure responsive device and said unloading means, means operative at a predetermined pump discharge pressure for supplying pressure fluid to said fluid conducting means, valve means for controlling the flow of pressure fluid through said conducting means relative to said pressure responsive device and operative in one position completely to vent pressure fluid from said pressure responsive device, separate means for conducting fluid under pressure relative to said unloading means, valve means for controlling the flow of pressure fluid through said last mentioned means, a power driven mechanism adapted to be driven by said power unit, means for controlling the connection of said power driven mechanism in driven relation with said power unit, and means connected for operation with said last mentioned means and adapted to effect actuation of said valve means to positions for venting fluid from said pressure responsive device and for supplying fluid to said unloading means when said power driven device is connected in driven relation with said power unit.

5. In combination, a power unit, a pumping apparatus connected for drive by said power unit, a pressure responsive device for controlling the supply of operating fluid to said power unit, pressure responsive unloading means for said pumping apparatus, means for conducting pressure fluid relative to said pressure responsive device and said unloading means, means operative at a predetermined pump discharge pressure for supplying pressure fluid to said fluid conducting means, valve means associated with said conducting means between the ends of the latter for controlling the flow of pressure fluid through said conducting means relative to said pressure responsive device, separate means for conducting fluid under pressure relative to said unloading means, valve means for controlling the flow of pressure fluid through said last mentioned means, a power driven mechanism adapted to be driven by said power unit, means for controlling the connection of said power driven mechanism in driven relation with said power unit, and means operatively connected with said last mentioned means for controlling the operation of both of said valve means.

RALPH E. LAMBERTON.
